ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

WARP STOP MOTION.

1,419,077.

Specification of Letters Patent. Patented June 6, 1922.

Application filed May 11, 1921. Serial No. 468,533.

To all whom it may concern:

Be it known that I, ALONZO E. RHOADES, a citizen of the United States, residing at Hopedale, in the county of Worcester and 5 State of Massachusetts, have invented an Improvement in Warp Stop Motions, of which the following description, in connection with the accompanying drawings, is a specification, like characters on the drawings representing like parts.

This invention relates to warp stop motions for looms wherein a series of drop wires are normally supported by the warp thread during weaving, and when a warp 15 thread becomes broken or too slack for weaving purposes, the associated drop wire drops into position to act through a train of mechanism to effect loom stoppage.

In that type of warp stop motion wherein 20 the detector passes through openings in a row or bank of drop wires, the arrest of the detecting movement of the detector by a drop wire is utilized to stop the loom. In such cases, however, defective action of the 25 warp stop motion is liable to occur by reason of the accumulation of lint on the detector, so that when a drop wire is dropped by a broken or abnormal slack warp thread, the lint will preclude the interengagement of 30 the detector with the narrow slot or opening in the drop wire, and the loom will continue to run under such conditions and produce imperfect cloth.

The object of the present invention is to 35 overcome this defective action in the warp stop motion of the type indicated, and to insure effective engagement of the detector and a drop wire, so that when a warp thread breaks or becomes too slack for weaving purposes, the dropped wire in co-operation with 40 the detector will unerringly effect loom stoppage.

An important feature of the present invention, therefore, consists of a detector 45 which partakes of its detecting movement in the widened portion of the opening in the drop wires when the latter are held raised by normal warp threads, and in which the construction of the detector and the upper 50 portion of the opening in the drop wires is such that effective operation of the stop mechanism will be effected when a drop wire fails to be held raised by any warp thread even though lint be accumulated on 55 the top of the detector.

Other novel features of construction and combination of parts in addition to the above will hereinafter be described in connection with the accompanying drawing, which shows a good practical form of the present 60 invention.

In the drawings:—

Fig. 1 is an enlarged or exaggerated sectional view through the detector showing the drop wire in side elevation, and held 65 raised by an intact or normal warp thread;

Figs. 2 and 3 are views similar to that of Fig. 1, showing the detector and its oscillating movement in the widened portions of the openings of the drop wires when the latter 70 are held raised by normal warp threads;

Fig. 4 is a view similar to that of Fig. 1, but with the drop wire dropped by a broken warp thread, and showing the engagement 75 of the detector and the upper slotted portion of the dropped wire;

Fig. 5 is a perspective view showing a series of drop wires held raised by normal warp threads, and the detector passing through the engaged openings of the drop 80 wires.

The drop wires 1, except as hereinafter more fully explained, may be of usual construction. As shown, each of the drop wires has the lower portion thereof formed 85 of legs 2, and through the opening therebetween passes the controlling warp thread 3. The drop wires, as indicated in Fig. 5, are arranged in one or more rows, and the warp threads 3 pass over the warp supports 4 at 90 opposite sides of the drop wires, and, in the present instance, the warp threads pass through the opening between the legs 2 of the drop wires. The above described construction may, however, be of any usual 95 type, the essential being that the drop wires may be held raised by normal warp threads.

Each of the drop wires is provided with an opening, which, in the present instance, is shown in the upper portion of the drop wires at 5. Through the openings 5 in the drop wires the detector 6 passes, and the size or width of the openings 5 is such that when the drop wires are held raised by intact warp threads, the detector may partake 100 of its detecting movement without restraint by any of the drop wires. In the present instance, the detector 6 is connected with a vibrating arm 7, and is given an oscillatory movement through a train of mechanism, 105 110

many forms of which are well known in the art. Since the details of the mechanism which is connected to the arm 7 forms no part of the present invention, and are well understood by those skilled in the art, illustration and description of such mechanism is not deemed necessary to enable those familiar with warp stop motions to construct and operate the invention.

- 10 The detector 6 is formed of a bar non-circular in cross section which extends from side to side of the loom, as indicated in Fig. 5, and when all of the drop wires are held raised by normal warp threads, the detector 15 or bar 6 will be oscillated in the widened portion of the opening in the drop wires. Should a warp thread break or become too slack, the associated drop wire will drop under its own weight, and in this general 20 type of warp stop motion, the detector at such times is engaged by a narrow slot in the upper portion of the drop wire, and according to the purpose of this type of warp stop motion, the detector will be arrested in 25 its oscillating movement and effect loom stoppage.

During weaving, lint is liable to accumulate on the detector, and in such case the lint is liable to prevent effective engagement 30 of the detector with the narrowed slot or opening in the top portion of the drop wire.

In the present invention, however, the detector and the narrowed opening or slot in the drop wires are so constructed that even 35 should lint accumulate upon the detector, during weaving, it will not interfere with the effective engagement of the detector and the narrowed slot or opening in the drop wire when a warp thread breaks or becomes too 40 slack.

The detector 6 has its side walls 8 non-parallel. These side walls converge upwardly, so that a cross section of the detector is substantially wedge-shaped, as clearly 45 indicated in the drawings.

The drop wires are each provided with a narrow opening or slot 9, the side walls 10 of which preferably converge upwardly as shown. The entrance to the narrowed slot 9 50 in a detector is widened, as indicated at 11, and the side walls of the narrowed opening curve inwardly without an abrupt change in direction, and converge upwardly up to the end wall 12.

55 The side walls 10 of the narrowed opening in the detectors may advantageously converge upwardly at the same angle as the converging side walls 8 of the detector, but the slot 9 is sufficiently deep and narrowed near 60 the end wall 12, that the wall 12 does not rest upon the detector when the drop wire is released by a warp thread, but, on the contrary, a space is provided between the end wall 12 and the top of the detector when the 65 drop wire is lowered to its stopping posi-

tion, in which the accumulated lint on the detector may be accommodated. The construction is such that when a drop wire is released by its controlling warp thread, it will drop, and the wedge-like detector will be 70 engaged by the wedge-like opening at the upper end of the drop wire, and owing to the converging character of the walls of the detector and opening 9 of the drop wires, the interengagement of the detector and narrowed opening in a drop wire will be made effective to arrest the detecting movement of the detector, even though lint may have accumulated on the detector.

75 From Fig. 4 it will be noted that the width 80 of the narrowed opening 9 in the drop wire adjacent the end 12 is made less than the width of the detector, so that when a drop wire is released by a warp thread, the side walls 10 of the opening 9 engage the side 85 walls of the detector, and the drop wire is supported thereby, with the end wall 12 of the opening 9 some distance above the top of the detector, consequently, a space is provided between the top of the detector and 90 the wall 12 of the opening in the drop wire for the accommodation of any lint that may have accumulated on the detector. The consequence is that even though lint be accumulated on the top of the detector, the drop wire 95 will functionally engage the detector and arrest its movement when released by a warp thread.

95 In the present instance of the invention, it should be noted that the narrowed openings 9 in the drop wires and the widened 100 openings 5 are located above the warp threads, and such disposition of the openings and warp threads is advantageous for some purposes. With certain classes of goods it 105 may be desirable to position the detector and the openings 5 and 9 of the drop wires below the sheet of warp threads, but in either case the essential is that the character of the detector and the narrowed slot or opening in 110 the drop wires be such that regardless of the accumulation of lint upon the detector, effective engagement may be had between the detector and a drop wire when the latter fails to be supported by a warp thread. 115 This characteristic of the present invention, is of importance because the drop wires 1 are necessarily very light, in order to prevent injury to the warp threads which support them.

120 What is claimed is:—

1. In a warp stop motion for looms, the combination of a detector of non-circular cross-section, a plurality of drop wires each having a wide opening through which the 125 detector passes and in which it has a detecting movement when the drop wires are supported by normally conditioned warp threads, and each having a detector arresting opening with converging side walls the up- 130

- per portion of which arresting opening is narrower than the width of the upper portion of the detector to form a lint receiving space between the top of the detector and the upper end of the opening when a drop wire fails to be supported by a warp thread. 5
2. In a warp stop motion for looms, the combination of a detector having upwardly converging side walls, drop wires each of 10 which has a wide opening in which the detector has a detecting movement, and an upper narrow opening the side walls of which converge upwardly to conform to the inclination of the converging walls of the 15 detector that the converging walls of the drop wire may move into wedging engagement with the walls of the detector to arrest the detector when a drop wire fails to be supported by a warp thread, the narrow 20 opening being extended upwardly beyond the point to which the detector enters therein thereby to provide a lint receiving space between the end wall of the narrow opening and the top of the detector. 25
3. In a warp stop motion for looms, the combination of a detector of non-circular cross-section, a plurality of drop wires each 30 having a wide opening through which the detector passes and in which it has a detecting movement when the drop wires are supported by normally conditioned warp threads, a warp thread receiving opening below and spaced from the detector receiving opening, and a detector arresting opening 35 extending upwardly from the detector receiving opening and having a width sufficiently narrow to engage the side walls of the detector when a wire drops to thereby arrest the downward movement of the wire
- before the detector contacts with the upper 40 end of the opening, whereby a lint receiving space is formed between the top of a detector and the upper end of the opening. 4. In a warp stop motion for looms, the combination of a detector having a narrow 45 upper and a wider lower surface, a plurality of drop wires each of which has a wide opening through which the detector passes and in which it has a detecting movement when the drop wires are held raised by the warp 50 threads, and a narrower opening having inclined walls that are a less distance apart near their upper end than the width of the detector, that a drop wire may be supported on the detector by engagement with the sides 55 thereof, thereby leaving a lint space between the end of the narrow slot and the top of the detector.
5. In a warp stop motion for looms, the combination of a detector of non-circular 60 cross-section, a plurality of drop wires each having a wide opening through which the detector passes and in which it has a detecting movement when the drop wires are supported by normally conditioned warp 65 threads, and a detector arresting opening extending upwardly from the wide opening and having its side walls positioned to receive and firmly engage the side walls of the detector when a wire drops, thereby to 70 arrest the downward movement of the wire with the upper end of the opening spaced from and providing a lint receiving space between it and the top of the detector.

In testimony whereof, I have signed my 75 name to this specification.

ALONZO E. RHOADES.
